John L Barnes

—Inventor

UNITED STATES PATENT OFFICE

JOHN L. BARNES, OF WHIGVILLE, OHIO

LIFTING JACK

Application filed March 20, 1926. Serial No. 96,247.

This invention relates to lifting jacks and the object thereof is to provide a lifting jack embodying a single throw lever of novel construction.

- 5 A further object thereof is to provide a jack of the character described embracing a vertically adjustable lever whereby the height to which the rack bar is moved may be regulated.
- 10 A still further object thereof is to provide a jack of the character described embodying certain novel features to be brought out more clearly in the following specification, and which is simple in construction, efficient in 15 operation, and inexpensive to manufacture.

In the drawings:—

Figure 1, is a side elevational view of my invention;

20 Figure 2, is a front elevational view thereof;

Figure 3, is a vertical sectional view thereof; and,

25 Figure 4, is a detail elevational view of the rack bar used in connecting with my invention.

Referring to the drawings wherein is shown a preferred form of my invention, the numeral 1 indicates a frame wherein is mounted a rack bar 2 having a head 3 formed 30 at the upper end thereof and carrying a roller 4 mounted in the lower end, said roller being adapted to bear against the interior of the frame 1 when the bar 2 moves. The bar 2 carries an integral laterally extending shoulder 35 adjacent its lower end, said shoulder being adapted to operate within a slot 6 in the frame 1 and having its movement limited by the extent of slot 6. A second roller 7 is mounted adjacent the upper end of the frame 40 1 and is adapted to bear against the rack bar 2 whereby movement of the same is facilitated.

Formed in the bar 2 and near the lower end thereof is a rack 8 which, when the bar is 45 raised, (by means to be described later) is adapted to be engaged by one end of a member 9 pivoted to the frame 1 as indicated at 10 and having a spring portion 11 integral with its lower end whereby the member 9 is kept in 50 engagement with rack 8 until such time as

the operator may desire to release the rack bar 1 which is accomplished by manipulation of the handle 12 secured to the member 9 as indicated by the numeral 13.

Means are provided for raising the bar 1 55 comprising a segment 14 carrying pins 15 which are adapted to firmly engage the bar 1 by entering openings 16 therein whereby upon proper movement of the segment 14 the bar may be raised. The segment 14 is 60 fixed on a pintle 17 rotatably mounted in members 18 supported on either side of said segment 14 exteriorly of ears 19 which are formed integral with the frame 1. The lower ends of the members 18 engage and are supported by racks 20 integral with the ears 19 and are kept in engagement therewith by means of flat springs 21 carried at the upper ends of the members 18 and bearing against the ears 19 as shown more clearly in Figure 70 2. It is thus evident that segment 14 may be raised or lowered, the pintle 18 moving in slots 22 formed in ears 19, whereby the extent of throw of the rack bar 2 may be regulated. The segment 14 has a shank 23 formed integral therewith and having depressions 24 formed on either face thereof for the reception of a cam lock 25 pivotally mounted in the member 26 which receives a reduced portion 27 of a hand grip 28 whereby a lever is 80 formed said structure being separable for packing in a small space or a longer lever may be secured by inserting a handle of the desired length in the outer open end.

Having described my invention, what I 85 claim as new and desire to secure by Letters Patent, is:—

1. A jack of the character described comprising a frame, laterally extending ears integral therewith, a bar adapted to reciprocate in the frame, and provided with openings, roller bearings carried by said frame and bar, a segment carrying pins adapted to enter the openings in the bar, a pintle on which said segment is fixed and having the ends thereof 90 extending through slots formed in the laterally extending ears of the frame and rotatably mounted in members arranged exteriorly of the ears and longitudinally adjustable thereon, a handgrip detachably secured to 95 100

the segment, and means for maintaining the bar in its raised position.

2. A jack of the character described comprising a frame, laterally extending ears integral therewith, a bar adapted to reciprocate in the frame, and provided with openings, roller bearings carried by said frame and bar, a segment carrying pins adapted to enter the openings in the bar, a pintle on which said segment is fixed and having the ends thereof extending through slots formed in the laterally extending ears of the frame and rotatably mounted in members arranged exteriorly of the ears, said members engaging racks on the ears whereby they may be adjusted longitudinally, springs urging said members into engagement with said racks, a handgrip detachably secured to the segment, and means for maintaining the bar in its raised position.
3. A jack of the character described comprising a frame, laterally extending ears integral therewith, a bar adapted to reciprocate in the frame, and provided with openings, roller bearings carried by said frame and bar, a segment carrying pins adapted to enter the openings in the bar, a pintle on which said segment is fixed and having the ends thereof extending through slots formed in the laterally extending ears of the frame and rotatably mounted in members arranged exteriorly of the ears, said members engaging racks on the ears whereby they may be adjusted longitudinally, springs urging said members into engagement with said racks, a handgrip detachably secured to the segment, means for maintaining the bar in its raised position comprising a rack formed on the lower end of the bar, a spring pressed member carried by the frame, and engaging said rack when the bar is moved upwardly, and a handle for releasing the bar from engagement with the spring pressed member.

In testimony whereof, I affix my signature.

JOHN L. BARNES.
